CLAIM

The ornamental design for a display case for collectibles, as shown and described.

DESCRIPTION

FIG. 1 is a side perspective view of the display case for collectibles of this invention;

FIG. 2 is a top plan view of the display case for collectibles
of FIG. 1;

FIG. 3 is a side elevation view of the display case for
collectibles of FIG. 1;

FIG. 4 is a rear elevation view of the display case for
collectibles of FIG. 1;

FIG. 5 is a front elevation view of the display case for collectibles of FIG. 1; and,

FIG. 6 is a bottom plan view of the display case for
collectibles of FIG. 1.

The broken line disclosure is for illustrative purposes only and forms no part of the claimed design.
